UNITED STATES PATENT OFFICE

112,649

DESIGN FOR A POURING SPOUT CAP

Louie Frank Werner, Delphos, Ohio, assignor to
The New Delphos Manufacturing Company,
Delphos, Ohio, a corporation of Ohio

Application April 19, 1938, Serial No. 76,599

Term of patent 7 years

To all whom it may concern:

Be it known that I, Louie Frank Werner, a citizen of the United States and resident of Delphos, in the county of Allen and State of Ohio, have invented a new, original, and ornamental Design for a Pouring Spout Cap, of which the following is a specification, reference being had to the accompanying drawing, forming a part thereof.

Fig. 1 is a perspective view of a pouring spout cap showing my new design; Fig. 2 is an outer end view, and Fig. 3 is a side view thereof.

The dominant feature of my design resides in a pouring spout cap of the contour shown, having a truncated conical portion between the large and small cylindrical threaded portions, the base of which conical portion is of less diameter than the large threaded portion.

I claim:

The ornamental design for a pouring spout cap, substantially as shown and described.

LOUIE FRANK WERNER.
